UNITED STATES PATENT OFFICE

FRANK F. HOLLAND, OF PORTLAND, MAINE.

DESIGN FOR A RECEPTACLE.

SPECIFICATION forming part of Design No. 32,981, dated July 24, 1901.

Application filed June 21, 1900. Serial No. 21,109. Term of patent 7 years.

To all whom it may concern:

Be it known that I, FRANK F. HOLLAND, of Portland, in the county of Cumberland and State of Maine, have invented and produced 5 a new and original Design for a Receptacle, of which the following is a full, clear, and exact specification.

Reference is to be had to the accompanying drawings, forming a part of this specification, 10 in which similar characters of reference indicate corresponding parts in all the views.

Figure 1 is a plan view of a receptacle, showing my design. Fig. 2 is a sectional side elevation of the same on the line 2 2 in Fig. 1, 15 and Fig. 3 is a transverse section of the same on the line 3 3 in Fig. 1.

The invention relates to receptacles for in-

sertion in handled holders, and the receptacle in its entirety consists of a cup-shaped body A, having an annular flange B at the top, the flange having a slightly downward bend, and the body being deep and elongated, the side walls C at the major axis of the body being of parabolic shape, and the side walls D at the minor axis slightly bent inward and inward from the lower spherical bottom, as plainly shown in Fig. 3.

I claim—

The design for the receptacle shown and described.

FRANK F. HOLLAND.
